DESIGN FOR A CASING FOR A MARKING MACHINE

Turner B. Messick, Denver, Colo., assignor to
Burr Watson, Denver, Colo.

Application November 1, 1945, Serial No. 123,387

Term of patent 14 years

(Cl. D64—11)

To all whom it may concern:

Be it known that I, Turner B. Messick, a citizen of the United States, residing at Denver, in the city and county of Denver, State of Colorado, have invented a new, original, and ornamental Design for a Casing for a Marking Machine, of which the following is a specification, reference being had to the accompanying drawing, forming part thereof.

Figure 1 is a side elevational view of a casing for a marking machine showing my new design,

the back being plain and the opposite side presenting substantially the same appearance as the side shown.

Figure 2 is a front view of the casing for a marking machine.

The essential features of my design reside in the parts shown in full lines.

I claim:

The ornamental design for a casing for a marking machine, as shown and described.

TURNER B. MESSICK.
